UNITED STATES PATENT OFFICE.

HENRY RUWART, OF JEFFERSON CITY, MISSOURI.

SIDE-SADDLE.

SPECIFICATION forming part of Letters Patent No. 296,711, dated April 8, 1884.

Application filed January 29, 1883. (No model.)

To all whom it may concern:

Be it known that I, HENRY RUWART, of Jefferson City, Missouri, have made a new and useful Improvement in Side-Saddles, of which the following is a full, clear, and exact description, reference being had to the annexed drawings, making part of this specification, in which—

Figure 1 is a view in perspective of a side-saddle tree having the improvement; Fig. 2, a vertical transverse section of the tree and roll or rim; Fig. 3, a similar section of the tree, the foundation-covering being attached to the tree; Fig. 4, a sectional view of the roll, its covering being at one edge attached to the roll; Fig. 5, a vertical transverse section similar to that of Fig. 2, but showing the foundation-coverings upon the tree and roll; and Fig. 6, a view similar to that of Fig. 5, but showing in addition the outer cover.

The same letters of reference denote the same parts.

The present invention relates to the shape of the side bars, the roll or rim, and the manner of covering the bars and roll and finishing the saddle.

A A represent the side bars of the tree. In the direction of the transverse axis of the saddle the bars are flat at the top, as seen more distinctly in Figs. 2, 3, 5, 6. Otherwise the bars may be of the usual form. A foundation-cover, B, is then applied to the bars, as shown in Fig. 3.

C represents the roll or rim of the tree. It is made separate from the bars and then attached thereto by means such as the screws c c, Figs. 1, 2; but before attaching the roll to the bars a foundation-cover, D, is applied to the roll. One edge, d, of the cover is fastened,

as in Fig. 4, to the under side of the roll. The roll is then fastened by means of the screws c c to the side bars, after which the edge d' of the cover D is drawn down upon the roll and fastened to the side bars, as shown in Figs. 5 and 6. The saddle is then finished by means of the outer cover, E, which is passed over the bars and roll and suitably fastened at its edges to the side bars, substantially as shown in Fig. 6. This outer cover rests upon the bars toward the center of the saddle, but toward the roll the cover need not fit the tree closely, and the seat F, Fig. 6, in consequence is suitably rounded out at its periphery.

The intermediate covers B D, either or both of them, may be omitted, and only the cover E be used.

The strainer G is countersunk in the bars A A, as shown. This enables the seat F to be smooth without any ridge, as heretofore.

The tree is supplied to the trade with the roll attached. The saddle then, by unscrewing the screws c c, detaches the roll and then completes the saddle, as above described.

I claim—

1. A side-saddle tree having the strainer G countersunk in the side bars, as and for the purpose described.

2. The combination, in a saddle, of the flat-topped side bars, A A, the detachable roll C, and the cover E, substantially as described. 70

3. The combination of the side bars, A A, the cover B, the detachable roll C, the cover D, the fastenings c c, the cover E, and strainer G, substantially as described.

HENRY RUWART.
